WARM AIR HEATING SYSTEM

William L. Steele, near Seattle, Wash.

Application June 22, 1937, Serial No. 149,742

2 Claims. (Cl. 126—116)

My invention relates to furnaces, and more particularly to an arrangement of the parts thereof, as the combustion means, in combination with a hot air circulating system.

One of the primary objects of this invention is to lessen the number of parts in such a system, by adapting one part to perform the functions heretofore performed by parts now omitted, thus lessening the cost of the system, rendering it more compact, and simplifying its maintenance, all with no lessening of its efficiency, but rather with an increase in efficiency. In part these results are accomplished by omitting any separate blower for the supply of air for combustion, and by supplying such air by tapping the air circulating system, thereby obtaining air under pressure, removing from the circulating system a certain amount of air and forcing its replacement with fresh air, and effecting circulation of air through the circulation system immediately upon starting the burner or other combustion means.

With these and other objects in mind, as will appear hereafter, my invention comprises the novel parts and the novel combination and relative arrangement thereof, as shown in the accompanying drawing and as will be more particularly described herein and defined by the claims which terminate this specification.

In the accompanying drawing I have shown my invention embodied in an illustrative form, as now preferred by me, it being understood that various changes may be made in the form of the parts, and to some extent in their relative arrangement, without departing from the spirit of my invention.

Figure 1 is a general horizontal sectional view through the heating and air circulating plant, and Figure 2 is a general vertical section through the same, substantially on the line 2—2 of Figure 1.

The furnace as shown herein consists of a furnace body 1 supported upon the floor or upon a base 10, having within it an upright combustion chamber 11 open at its top and lined with fire brick or similar refractory material. A combustion means, such as the oil burner tip 2, enters the combustion chamber 11 through an inlet such as the sleeve 12, the burner tip being suitably supported in this sleeve. The products of combustion, emanating from the combustion chamber 11, pass into the upper part of the furnace body 1 and then pass downwardly and outwardly through a flue connection 13. Between the upper part of the furnace body 1 and

the flue connection 13 I prefer to arrange baffling means, such as the ring 14, supported upon the combustion chamber 11 and spaced slightly at its periphery from the inner wall of the furnace body 1, the purpose of this being to conduct the hot gases into intimate contact with the furnace body to heat the latter, and to abstract all possible heat from the hot products of combustion. The form of this furnace may be other than that described, and its particular form is not considered a part of the present invention.

Surrounding the furnace 1 is a casing 3 of appropriate shape, preferably rectangular in plan, and partitioned, as indicated at 30, to provide a space 31 wherein the air is heated by contact with the furnace 1, from which leads the hot air conduit 34, and a chamber or extension 32, all within the casing 3, to which chamber 32 the cold air return pipe 33 is connected.

Between the chamber 32 and the chamber 31, and preferably within the chamber 32, is disposed a blower 4, arranged to receive air from within the chamber 32 and to discharge it at 40 through the partition 30 and into the hot air chamber 31, preferably at the bottom of the latter chamber. This blower, while in operation, effects positive circulation of the air throughout the system.

Usually the oil burner, coal stoker, or other combustion means is a unit, including an oil pump, a blower, and regulating means, and when it is connected to a furnace it extends outwardly from the furnace, obstructing space that can be used for no other purpose. To achieve all the advantages of my invention the oil burner is separated into a tip element and an oil pump, so located relative to other parts of the system as to occupy no otherwise usable space, and the blower is omitted entirely. I do not claim as my invention the mere separation of the parts of the burner, but rather their location relative to other parts of the system, and the means whereby air under pressure is supplied for combustion, notwithstanding the omission of the usual blower of such a burner.

The oil pump 20 is preferably located within the extension 32 of the casing, where it is within the general plan of the furnace casing. From it extends the pressure pipe 21 to the tip 2, and to it are connected the supply pipe S and the return pipe R, connecting the pump with the storage tank (not shown). The oil supply line 21 may extend between the burner tip 2 and the pump 20 externally of the casing 3, or it may lie within the casing. Preferably it is outside, in

45

55

part, at least, for it occupies no appreciable space, and is more accessible when the tip must be cleaned, and there is provided a cut-off or regulating valve 22 adjacent the burner tip. The sleeve 12 admitting to the burner tip is closed by a removable door 15 through which the oil supply line 21 passes.

Also within the extension 32 is a motor M connected to drive the blower 4 and the oil pump 20. Such a connection is indicated by the belt B. A box T may also be supported within this chamber 32 for housing a transformer, electrical controls, and connections for ignition points P terminating adjacent the burner tip 2. A filter F may be interposed between the cold air return conduit 33 and the inlet to the blower 4, likewise in the extension 32, and as is usually the case, such filters are arranged for inspection and replacement. Other devices sometimes employed in such systems, as a humidifier, may be incorporated, but are not shown, as they form no part of the invention.

Air must be supplied to the interior of the furnace adjacent the burner tip 2, in order to support combustion. Usually this must be supplied under pressure. Since the furnace is closed and the outer end of the sleeve 12 is closed by the door 15, the sole supply of air to the burner is by means of a combustion air supply conduit 5 which taps the pressure side of the air circulating system to receive air from the latter, its end 50 being disposed at the discharge outlet 40 of the blower 4, and this conduit 5 leads thence to a connection to the sleeve 12, whence it issues surrounding the burner tip into the combustion chamber 11. Barring minor leakage, this conduit 5 constitutes the sole air supply for combustion, and this air is supplied under pressure from the air circulating system, but by so doing it eliminates the necessity of a separate blower for the burner. Similarly the employment of a single motor and the location of the oil pump adjacent the blower eliminates a separate motor for the drive of blower and oil pump, and further simplifies the system, and enables all parts to be compactly arranged so as to occupy a minimum of floor space.

Objections to the system described have been raised on the ground that it is not desirable to deliver air for combustion from that blower which effects circulation of air through the circulation system, for the reason that when the furnace is cold operation of the blower will circulate cold air through the house, yet the blower must operate to supply air for combustion. The burner, hence a blower so connected, must operate for some period of time before the furnace becomes heated sufficiently to affect or materially raise the temperature of the air in the house, and it has been considered undesirable to circulate the air before its temperature has been raised somewhat. It has been felt that this would have a tendency to cool the air within the house. For this reason, among others, burners have been supplied with a blower separate from the circulating blower,

and while the burner blower starts immediately the burner starts, the controls have been arranged to start the circulating blower only after the furnace has been heated to an appreciable temperature. This reasoning, however, is fallacious, for the air in the house is at a given temperature, and the furnace body is at substantially the same temperature, hence circulation of this air through the house does not cool the house, nor, or course, does it warm the house, but it does no harm and it brings the circulating air into contact with the furnace body so that the air is warmed as soon as the furnace body becomes heated to any degree, and thus gradually warms the house. Because the temperature of the house closely corresponds to the temperatures of the furnace, overrunning of the burner is less likely, and economy in the use of fuel and more even temperature results. Thus tapping the circulating air for the supply of air for combustion does no harm, and this arrangement effects a considerable economy of parts, economy of operation, lessens the difficulties of maintenance, and cuts down on the floor space of the installation as a whole.

What I claim as my invention is:

1. A hot air heating and circulating system including a furnace body having an opening in a side, a casing surrounding the same, and partitioned to define a hot air chamber immediately about the furnace body and a cold air chamber at one side of the hot air chamber, the casing having an opening through a side and registering with the opening in the furnace body, a sleeve joining said two openings, a burner tip received in said sleeve to discharge within the furnace, and accessible for removal or adjustment from without the casing, means within the cold air chamber to effect air circulation from the cold air chamber to the hot air chamber, a conduit tapping said air circulating means to conduct a portion of the air to the sleeve, a fuel pump within the cold air chamber, and a conduit connecting said fuel pump to the burner tip.

2. A hot air heating and circulating system including a furnace body having an opening in its side, a casing surrounding the same, and partitioned to define a hot air chamber immediately about the furnace body and a cold air chamber at one side of the hot air chamber, the casing having an opening through its side registering with the opening in the furnace body, a sleeve joining said registering openings, a burner tip received in said sleeve to discharge within the furnace body, and accessible for removal or adjustment from without the casing, a conduit for conducting combustion air to the sleeve, and means within the cold air chamber to effect a circulation of air from the cold air chamber to the hot air chamber and a supply of air to the conduit, a fuel pump within the casing, distant from the burner tip, and a conduit connecting the fuel pump to the burner tip.
